CORN POPPER

Walter E. Moore, Belnol, Mo.

Application December 18, 1956, Serial No. 44,237

Term of patent 14 years

(Cl. D81—10)

Fig. 1

Fig. 2

Fig. 3

Figure 1 is a front elevational view of a corn popper, showing my new design;

Figure 2 is a top plan view thereof; and

Figure 3 is a side elevational view from the right side of Figure 1.

I claim:

The ornamental design of a corn popper, substantially as shown.
